Attorney.

UNITED STATES PATENT OFFICE.

HAROLD E. THOMPSON, OF INDIANAPOLIS, INDIANA.

PHONOGRAPH-RECORD-PLAYING REPEATER.

1,412,148.

Specification of Letters Patent. Patented Apr. 11, 1922.

Application filed August 23, 1920, Serial No. 405,436. Renewed December 12, 1921. Serial No. 521,928.

To all whom it may concern:

Be it known that I, HAROLD E. THOMPSON, a citizen of the United States, residing at Indianapolis, in the county of Marion 5 and State of Indiana, have invented new and useful Improvements in Phonograph-Record-Playing Repeaters, of which the following is a specification.

So far as I am aware inventive effort to 10 provide an attachment for phonographs that will automatically cause a repetition at will of any record-disk played thereon, has only succeeded where certain adjustments of the attachment were made each time one 15 record-disk was changed for another with impressed record briefer or longer than the one previously played. This inconvenience to users unskilled in mechanical adjustments has appeared so great that such attachments 20 have failed of popularity and common use; but the pleasure derived from an automatic repeating device would cause its popular acceptance were the above difficulty overcome.

25 It appears that the possibility of incorporating into each record itself the control that would otherwise have to be in the attachment has apparently been overlooked, and I have therefore resorted to such 30 means for eliminating the inconvenience mentioned and have produced a variety of devices which obtain the desired end in a simple manner, of which a representative form is illustrated herewith and described 35 in the following specification.

The object of this invention is to provide 40 a device readily applicable to all commercial types of phonograph apparatus, and automatically operated from the sound-record disk, for lifting the stylus out of contact with the disk after it has played a record, and transferring it to the place of beginning into contact with the disk in order to repeat the reproduction of the sounds recorded upon said sound-record disk.

The object further is to provide this device of such construction and operation that if expedient to specially prepare the record disk the device will function accurately with 50 successive records without any adjustments of the device itself; or, if standard unprepared record disks are used, a simple temporary preparation of the record disks will suffice to effect an accurate adjustment to 55 offset the variation that exists between respective record disks in the distance from

the center at which the recorded musical or other selection terminates.

A further object is to provide such construction of this device that no part will 60 drag on or rub the surface of the record disk and thus tend to mar its perfection of impressed selection, or even the perfection of its polish or glossy finish which might suggest damage to the record disk. 65

A still further object is to provide a device that will so operate as not to noticeably retard the rotative speed of the record disk or cause it to slip upon the revolving turn-table from which its motion of revolution 70 is derived, or in any way tend to cause stoppage of a weakly-powered phonograph, or the cessation of useful operation due to record slippage.

I accomplish the above, and other objects 75 which will hereinafter appear, by the mechanism illustrated in the accompanying drawing, in which:

Fig. 1 is a top plan view of a phonograph and cabinet with my invention operatively 80 applied. Fig. 2, is a vertical section on the line 2—2 of Fig. 1. Fig. 3, is a side elevation of the sound-box and its supporting sleeve with my invention applied, the record-disk and turn-table being in section 85 with the stylus in the groove of the disk bringing the cone-wheel of the repeater into contact with the disk. Fig. 4, is a view in rear elevation of the sound-box and associated parts shown in Fig. 3. Fig. 5, is a 90 section on a larger scale of part of a sound-record disk embodying my invention in so far as the disk is concerned, and Fig. 6, is a like view of a modified form of disk.

Like characters of reference indicate like 95 parts in the several views of the drawing.

Referring now to the drawing, the reference character 5, indicates a cabinet having a horizontal partition or floor 6, below which is a spring, electric, or other usual or suitable motor-mechanism (not shown) for rotating a turn-table 7, on which a sound-record disk 8, is mounted in the usual manner. In the form shown in Fig. 1, a motor-driven shaft 9 has a pulley by which it is connected 100 by a belt 10, with the turntable. A switch 11 is for starting and stopping the motor, and 12 is an indicator-control for regulating the speed of the turntable. A tone-arm 13, 105 discharges into a sound-deliverer under floor 6, of usual or suitable construction (not shown). The tone-arm is jointed in the 110

usual manner at 14, to permit the outer member to fold up and back, and the arm as a whole has horizontal oscillatory adjustment on its vertical end 15. The opposite 5 end of the tone-arm terminates with a transverse split sleeve 16, with clamping flanges at the split which are brought toward each other by a screw 17. Mounted in the split sleeve 16, is a cylindrical sleeve 18, adapted 10 to be adjusted both rotarily and longitudinally of itself when screw 17 is loosened sufficiently and a given adjustment is retained by tightening the clamp controlled by the screw 17. The sleeve 18 is hollow and 15 mounted therein is a hollow sleeve 19, to a projecting end of which is fixed the sound-box 20; and between the latter and split sleeve 16, is an extension 21, from the sound-box, having a worm-gear wheel 22, engaged 20 by a worm on shaft 23. The upper end of shaft 23 is mounted in a journal-box on the end of an arm 24, carried by the sleeve 18. The lower end of the shaft 23 passes through the bent lower end of an arm 25, also carried 25 by the sleeve 18, but, to provide a resilient adjustment to the shaft longitudinally, the end of the latter is preferably passed through arm 25, as shown in Fig. 4, and rests upon a spring 26 carried by arm 25. Mounted 30 in a fixed manner on the shaft 23, is a friction wheel 27, preferably in the form of a conical frustum as shown, and interiorly hollow for the assembly therein of a rubber or other like sort and tractile material 28, 35 which projects below the lower edge of the wheel to make rolling contact with the sound-record disk when suitably lowered; and in order to contact only a portion of the complete circular projection I incline the 40 shaft 23, inwardly, or with its lower end further in than its upper end toward the center of the disk 8, and also closer to a vertical plane through the axis of sleeve 18, which causes the wheel 27 to roll toward the 45 outer edge of the sound-record disk 8 by contact with the disk when the disk is rotating. At the upper end of the journal-box carried by the arm 24, is a set-screw 29, by which the shaft 23 may be adjusted longitudinally 50 against spring 26, to vary the elevation of wheel 27 above the sound-record disk 8, for purposes which will hereinafter appear.

Connected with the sound-box 20 are the usual fulcrum-projections upon which the 55 pivot-frame 30 of an upwardly extending vibrator-arm 31 is pivoted, and the upper end of the arm 31 is connected with the diaphragm of the sound-box (not shown) in the usual manner. Connected with and ex- 60 tending downwardly from the pivot-frame 30 is the stylus-holder 32, in which is the stylus 33, adapted to contact operatively with the sound-record impressions of the sound-record disk. It is held by the set- 65 screw 34.

On the back of the sound-box is a single lug 35, which contacts the round end of a spring-pressed pin 37, mounted in a socket in an adjustable screw 36, in a standard carried by the sleeve 18. A milled wheel 38' on the screw 36, allows the pin 37 to be carefully adjusted with relation to the lug 35, to just resist the rotary tendency of the sound-box caused by the drag of the stylus against the rotating sound-record disk; but anything greater, as by the drive of wheel 27, through the worm-gear, by the contact of said wheel with the rotating sound-record disk, will carry the lug 35 past the pin 37, and cause the sound-box to be rotated thereby lifting the stylus away from the disk, as shown by dotted lines in Fig. 4. Hence, it is important to adjust the elevation of the wheel 27 above the sound-record disk 8, by means of set-screw 29, as previously stated.

Between the sound-record impressions of the sound-record disk 8, and the center of the disk, and connected therewith to form a continuation of the said impressions, 90 which, as is well known, follows in spiral grooves, I provide an additional groove 38 enough deeper than the sound-record grooves to sufficiently lower the point of the stylus to rest the weight that has been supported by it upon the friction-wheel 27, as shown in Figs. 3 and 4, and thereupon shaft 23 and its worm will be rotated by the action of the moving disk 8 on wheel 27, and the worm-wheel connected with the sound-box 100 20 will be rotated, correspondingly rotating the latter. The wheel 27 will roll toward the outside of the disk 8, until arrested by contact with a stop seated in the cabinet floor 6, and extending up in the path of the tone-arm 13. This is a standard 39, terminating with a head having a threaded hole through which a set-screw 40 is screwed, to secure an adjustable stop.

When the outward travel of the wheel 27 110 across the disk 8 is arrested the wheel will continue to rotate thereby rotating the sound-box 20 until the latter sufficiently completes a revolution to bring the stylus again into contact with the disk, whereupon the drag or 115 friction of the disk against the stylus will continue the rotation of the sound-box lifting the latter and attached friction-wheel until the friction wheel is quite out of contact with the disk and until the further rotation of the sound-box is arrested by the contact of its lug 35 with the spring-pin 37. The position of the stylus is then such as to support the load from the disk 8 and to prevent contact between the friction wheel 120 27 and disk 8. The stylus will then follow the record lines of the disk until it again reaches the groove 38, whereupon the above operations will be repeated.

In the modification shown in Fig. 6, in- 130

stead of providing a groove 38 for the stylus to drop into and lower the wheel 27 into contact with the disk 8, I have shown a raised center plane or plateau 41, with which 5 the wheel will contact and on which it will ride and be rotated thereby rotating the sound-box and lifting the stylus out of contact with the record in the same manner as above described.

10 So far as I am aware, I am the first to control a repeating mechanism from a formation attached to or made in the sound-record disk and I therefore do not desire to be limited to the groove or plateau means 15 shown as it is evident that many substitutions may be made without substantially departing from the spirit of my invention as shown in the accompanying drawings, several of which I have embodied in opera- 20 tive devices (not shown) and to more fully elucidate the claims will here briefly de- scribe:

(1.) A substitute form of speed reducing mechanism (not shown) for the worm and 25 wheel shown, with the wheel 27 advanta- geously set with its axis substantially parallel to the plane of the record disk would function identically as if this axis in extension passed on the proper side of and at a proper 30 distance from the vertical axis about which the record disk revolves. This form would admit of a smaller wheel but gives a dis- 35 advantageous wheel location with reference to the stylus 33.

35 (2.) For the wheel 27 in the substitution above noted two or more wheels may be used (not shown), one contacting with the record disk to raise the sound box and stylus and the other contacting with the disk to 40 cause the lowering of the sound box and stylus when the first wheel has over-traveled and overhangs the outer edge of the record disk. This form would operate to lower the stylus at the outer edge of the disk regard- 45 less of the disk's diameter and without the necessity of an adjustable stop such as stand- 50 ard 39 with its set screw 40, but on account of the disadvantageous location of the wheels with reference to the stylus this modification would not be dependable for accuracy of operation.

55 (3.) An oscillating movement of the stylus 33 might be substituted for the rotary movement about the lengthwise axis of sleeve 19 by displacing the worm drive shown, by a suitable crank, eccentric, or cam mechanism (not shown) operatively connected with wheel 27 or one of its suggested substitutes. The axis of oscillation 60 may then be shifted to the end 14 of the tone arm 13, and the various sleeves 16, 18, 19 and their related parts omitted or greatly simplified. This would simplify the structure but the lessened travel of the stylus 65 33 would demand a too gradual retreat from

and approach toward the surface of disk 8, with consequent peculiarities of operation.

(4.) It is evident that the raised plateau might be a raised ring, or ring sector, or even a mere bump (not shown) of relatively 70 small dimensions which might contact wheel 27 two or more times before imparting to the latter enough rotative displacement to initiate its functioning, and that this raised portion might be integral with or adhesively 75 secured to or merely held by its own weight against the surface of disk 8; also that this raised portion, if not integral with the record disk, might be associated with various record disks successively, and might be of 80 metal, paper, rubber or other suitable material with various perforations (not shown) by which it could be selectively placed over the center pin of the record disk carrying table 7, to obtain various ef- 85 fective operating distances from the center pin. This would require individual record disk adjustment but would be simple and effective.

(5.) It is evident that the additional 90 groove 38 may be reduced in length and so arranged that the stylus 33 may dip into it two or more times (construction not shown) thus contacting the wheel 27 with record disk 8 a corresponding number of times be- 95 fore imparting to wheel 27 sufficient angular movement to effect its automatic functioning. This would give a groove that would not need to be crescent-shaped and there- 100 fore would be more readily produced in a previously unprepared record disk, but without a gradual descent and ascent the sound box would be jarred and unpleasant noises created.

(6.) It is evident that instead of being 105 arranged to under-travel any wheels such as wheel 27, the raised portion of disk 8 may by means of its edge rather than of its top surface, contact the side rather than the periphery of such wheel (not shown) 110 or might contact some intermediate lever or trigger (not shown) to cause the such wheel to move in its bearings or with its bearings relative to the sound box and stylus, and derive rotative motion by contacting 115 with the surface of record disk 8. This specific form when appropriately arranged would give very desirable definiteness of operation but the resulting side pressure would tend to cause the stylus 33 to jump 120 from one convolution of the sound record groove back into the previous one, creating disagreeable sounds and preventing the functioning of the repeating mechanism.

It is also evident that any other equally 125 obvious substitutions will not depart from the spirit of my invention; but what I claim as new and desire to secure by Letters Patent, is:—

1. In a player-repeater for phonographs,

a rotating sound-record disk, a rotatable sound-box, and a stylus moving with the sound-box, in combination with means comprising a roller to return the sound-box and stylus to first sound-reproducing position on the disk, means cooperating with the roller for rotating the sound-box to lift the stylus from the disk before beginning said return, and means in the structure of the disk for initiating the functioning of said first means.

2. In a player-repeater for phonographs, a rotating sound-record disk, a rotatable sound-box, a stylus moving therewith, means adapted to roll upon the surface of the disk when functioning for returning the sound-box and stylus to first sound-reproducing position on the disk, and means in the structure of the disk for rotating the sound-box by said roll-means to vary the relation between the point of the stylus and the plane of the sound-record impressions of the disk thereby initiating the functioning of the sound-box and stylus-returning means.

3. In a player-repeater for phonographs, a rotating sound-record disk, a rotatable sound-box, a stylus moving therewith, a return carrier adapted to roll upon the surface of the disk when functioning, means operated by the rolling of the return carrier for rotating the sound box, and means for automatically starting the functioning of the return carrier.

4. In a player-repeater for phonographs, a rotating sound-record disk, a rotatable sound-box, a stylus moving therewith, a return carrier-wheel, means operated by the wheel to rotate the sound-box and disengage the stylus from the disk, and means for automatically starting the operation of the return carrier-wheel.

5. In a player-repeater for phonographs, a rotating sound-record disk, a rotatable sound-box, a stylus moving therewith, an automatic wheeled return carrier having means to first rotate the sound-box and move the stylus out of contact with the disk, and means for automatically starting the operation of the wheeled carrier.

6. In a player-repeater for phonographs, a rotating sound-record disk, a rotatable sound-box, a stylus moving therewith, means to rotate the sound-box and lift the stylus from the record, means not in contact with said record-disk while the phonograph is reproducing sound adapted to be moved into contact with the disk and first rotate the sound-box and then by rolling contact with said disk automatically return the stylus to first sound-reproducing position, and means revolving with the sound-record disk for transmitting initial rotative movement to said last means from said rotating sound-record disk thereby rendering said last means operative.

7. A sound-record disk for phonographs having sound-record formations and also having another formation adapted to lower a stylus with respect to the plane of said sound-record formations and thereby initiate a subsequent elevation of said stylus out of contact with any such record formations, a rotatable wheel cooperating with the disk, and stylus-elevating means operated by the rotation of the disk.

8. The combination, with a sound-record disk for phonographs having sound-record formations, of a stylus operating in said formations, roller-means operated by contact with said disk to move the stylus to the place of beginning of a sound record, and gear means operated by the rotation of said roller for lifting the stylus out of said sound-record formations, said disk having another formation to initiate said rolling contact and thereby initiate said stylus lifting and moving operations.

9. In a player-repeater for phonographs, a rotating sound-record disk, a movable sound-box, a stylus moving therewith, a wheel inoperative while the phonograph is reproducing sound, means revolving with said record disk to automatically bring the wheel into contact with the disk and means cooperating with the wheel during the contact of the wheel and disk to raise the sound-box and stylus and deposit the stylus in contact with the disk at the beginning of the sound-record thereon.

10. In a player-repeater for phonographs, a rotating sound-record disk, a rotatable sound-box, a stylus moving with the sound-box, means comprising a friction wheel to rotate the sound-box by contact of the wheel with the disk, means to resist rotation of the sound box and thereby hold the wheel away from the disk while a record is being played, and means on the record-disk to cause the friction wheel to contact the disk and thereby rotate the sound-box by overcoming said resisting means and thereby move the stylus out of contact with the disk when the stylus has reached the end of the record and then carry the sound-box and stylus to the place of beginning of the sound-record.

11. In a player-repeater for phonographs, a rotating sound-record disk, a rotatable sound-box, a stylus moving with the sound-box, a friction wheel out of contact with the disk while the record is being played, a rotative driving means operatively connecting said sound-box with the friction wheel, and means carried by the record to bring the wheel into contact with the record.

12. The combination with a sound-record disk for phonographs having sound-record formations, of a stylus operating in said formations, roller means operating by rolling contact with said disk, gear means operated by the rolling operation of the first
